UNITED STATES PATENT OFFICE.

PETER M. McNABB, OF JOLIET, ILLINOIS.

MOLD.

974,507.

Specification of Letters Patent.

Patented Nov. 1, 1910.

Application filed August 17, 1909. Serial No. 513,319.

To all whom it may concern:

Be it known that I, PETER M. McNABB, a citizen of the United States, and a resident of Joliet, in the county of Will and State of Illinois, have invented certain new and useful Improvements in Molds, of which the following is a specification.

This invention relates to improvements in molds for forming lay-figures such as are commonly used by dressmakers, tailors, and others, for fitting and draping gowns, dresses, and other garments.

The object of the invention is to provide a mold for this purpose, whereby a figure may be produced which will conform to the figure of the model, reproducing not only measurements but any lack of symmetry or peculiarities of posture.

To this end my improved mold comprises the various features and details of construction hereinafter described and claimed.

In the accompanying drawing, in which my invention is fully illustrated—Figure 1 is a perspective view of a lay-figure showing a mold of my invention applied thereto as it will, in practice, be applied to living models. Fig. 2 is a rear view of the back section of the said mold when removed. Fig. 3 is a fragmentary detail sectional view taken substantially on the line 3—3 of Fig. 1, showing the covering for the body of the mold and the means for connecting the different sections thereof; and Fig. 4 is an enlarged view of one of the strips of the mold shown in Fig. 3.

Referring now to the drawings, A designates a lay-figure, which is illustrative of a substantially half length view of a living model of which a facsimile lay-figure is to be produced, and B designates, as a whole, a mold of my invention shown in Fig. 1, applied to the lay-figure A, as in practice it will be applied to a living model.

The frame of the mold B is made of material of such character that it will be soft and plastic when heated, and will be set and rigid when cold. In practice I have used for this purpose what is commonly known to the trade and in the art as "modeling compound," commonly used by dentists for taking impressions of the mouths of patients. My invention, however, contemplates equally the use of any other material possessing the characteristics specified. In the preferable form thereof shown in the drawings, the frame of the mold B is a skeleton structure

consisting of strips of material 1 which extend lengthwise of the mold and, so far as possible, are preferably continuous from top to bottom thereof, and transverse strips 2 which connect said strips 1, thus forming spaces or openings 3 between said strips. My invention, however, contemplates equally constructing said molds from continuous sheets of material, if desired. Whichever construction is used, however, care must be exercised to provide a sufficient body of the compound so that it will retain its heat and plasticity for a sufficient length of time to permit it to be applied and conformed to the model, in the manner presently described. In practice, I have used, with highly satisfactory results, strips of compound 1 and 2 about $\frac{1}{4}$ of an inch wide by $\frac{1}{4}$ of an inch thick, the edges thereof being preferably rounded to render them less cumbersome and bulky.

The frame of the mold B comprises a plurality of different sections consisting, as shown, of a front section B¹ and a back section B², said sections being provided with suitable cut-out portions or openings for forming arm holes, neck openings, etc. To provide for removing the mold from the model, the sections B¹ and B² are detachably connected at their meeting edges, as by glove fasteners 4. To provide for taking up any "fullness" due to fitting or conforming the mold B to the model, one or both of the sections B¹ B², as shown, the back section B², is divided from top to bottom to form separate parts or pieces 6 and 7 so proportioned that, within their designed limits of use, the edges of said parts or pieces 6 and 7 will overlap, as shown at 8. The overlapping edges of said parts or pieces 6 and 7 are adapted to be connected in fixed adjustment after the mold has been fitted to the model in any desired or approved manner, as by strips on one thereof adapted to engage corresponding buckles on the other. Over the shoulders, the edges of said sections B¹ B² are also adapted to overlap, the overlapping edges thereof being connected in fixed adjustment as by straps and buckles, or in other desired manner.

The material or compound for forming the frame of the mold is preferably incased in a close fitting covering 9 of suitable pliable material, preferably light, strong fabric, as silk, cambric, or the like. As shown, said covering consists of pieces applied to

opposite sides of the frame of the mold B which are stitched together along the edges of the strips of compound 1 and 2. Said covering 9 will operate to prevent the strips 5 of material from which the frame of the mold is formed from breaking in handling when heated and while being fitted to the model, and, when the frame of said mold is cold and set, will operate to hold pieces of 10 said mold, which may be accidentally broken off, in proper position relative to other parts of said mold. Said covering 9 will also prevent the compound, when being applied to the model and while in a heated condition, 15 from coming into contact with and sticking to the clothing or person of the model in case said material is sticky when heated. To effect a close union between said covering and the material forming the frame of the 20 mold, said covering, in addition to being stitched in the manner described, will preferably be applied so as to adhere closely to the frame of the mold. Where the material of which the frame of the mold is made is 25 sticky when heated to a degree of desired plasticity, as is the case with modeling compound, this may be conveniently effected by applying said covering to the frame of the mold when heated. When the material 30 which forms the frame of the mold is not sticky when heated, it may be applied by means of a suitable adhesive.

While, due to the overlapping of the parts 35 or pieces 6 and 7 which form the back sections of the mold, any given mold is adapted for use in forming figures of persons varying considerably in size, a series of molds of different sizes will preferably be provided, to accommodate all sizes of people.

40 While I have shown my improved mold as made in two sections, this is merely illustrative, and my invention contemplates forming said mold in any desired number of sections.

45 The preferable method of forming my improved mold is as follows:—The parts or pieces 6 and 7 of the back section B² of the mold are first connected to opposite edges of the front mold section B¹, which can be conveniently done by means of the glove fasteners 4. The mold is then heated, a desirable temperature where modeling compound is used for making the mold, being about 165 degrees. When the compound is heated 50 throughout, the mold, now plastic, is applied to the model. Working rapidly on account of the limited time required for the compound to set and harden, the sections of the mold are adjusted around the neck and 55 arms of the model and connected over the shoulders by the means provided for that purpose. Beginning at the front, the mold is next fitted and adjusted to conform closely to the figure of the model, and, a desired fit 60 having been obtained, the overlapping edges 65

of the parts 6 and 7 forming the back sections B² of the mold are connected, as by the straps and buckles provided. The mold is then permitted to remain on the model until it becomes thoroughly set and rigid, whereupon the front and back sections B¹ and B² are detached from each other and removed from the model. In case it is desired to cast the lay-figure at a single operation, the sections B¹ B² are again connected, forming a 70 mold the interior of which will conform exactly to the figure of the model and from which an exact facsimile of the model may be made. If desired, however, the lay-figure may be cast in separate sections corresponding to the sections of the mold when removed from the model and then secured together. 75

In order that the lay figure, when finished, may have an even outer surface, particularly 80 where the mold is skeletoned, as shown in the drawing, said lay figure preferably comprises a covering consisting of continuous sheets or layers of suitable stiff material which, in molding said lay figure, is first applied to said mold in the form of a lining, 85 preferably in sections corresponding and conforming to the sections B¹, B² of the mold. Said sheets or layers thus applied will prevent the plastic material from which 90 the body of the lay figure is formed, from bulging or protruding through the openings in the mold, which would render the surface of said lay figure uneven or humpy. 95

A particular advantage which my improved mold possesses is that it may be used over and over again almost indefinitely in forming lay figures of different persons or models, whereas, all other molds for this purpose of which I have any knowledge, admit of being used for a single person or model only. 100

I claim:—

1. A mold the frame of which is made of material which is plastic when heated and is 110 set and rigid when cold, whereby when heated said mold may be conformed to the model and when cold will retain its shape during the molding of the figure, said frame comprising sections constructed and arranged to be detachably connected to each other, substantially as described. 115

2. A mold the frame of which is made of material which is plastic when heated and is 120 set and rigid when cold, whereby when heated said mold may be conformed to the model and when cold will retain its shape during the molding of the figure, said frame comprising sections constructed and arranged to be detachably connected to each other, said sections comprising a section consisting of parts constructed and arranged to overlap and to be connected together in fixed overlapped position, substantially as described. 125

3. A mold the frame of which is made of 130

material which is plastic when heated and is set and rigid when cold, whereby when heated said mold may be conformed to the model and when cold will retain its shape during the molding of the figure, said frame comprising sections constructed and arranged to be detachably connected to each other, and a flexible covering for the frame of said mold, substantially as described.

- 10 4. A mold the frame of which is made of material which is plastic when heated and is set and rigid when cold, whereby when heated said mold may be conformed to the model and when cold will retain its shape during the molding of the figure, said frame comprising sections constructed and arranged to be detachably connected to each other, and a covering of fabric for the frame of said mold, substantially as described.
- 15 5. A mold the frame of which is made of material which is plastic when heated and is set and rigid when cold, whereby when heated said mold may be conformed to the model and when cold will retain its shape during

the molding of the figure, said frame comprising sections constructed and arranged to be detachably connected to each other, and a flexible covering for the frame of said mold applied thereto by means of an adhesive, substantially as described. 25

6. A mold the frame of which is made of material which is plastic when heated and is set and rigid when cold, whereby when heated said mold may be conformed to the model and when cold will retain its shape during the molding of the figure, said frame being skeletoned and comprising separate sections constructed and arranged to be detachably connected to each other, substantially as described. 30

In testimony, that I claim the foregoing as my invention, I affix my signature in presence of two subscribing witnesses, this 12th day of August, A. D. 1909.

PETER M. McNABB.
